UNITED STATES PATENT OFFICE

103,877

DESIGN FOR A THERMOSTAT MECHANISM

Morton O. Snediker, Chicago, Ill., assignor to The Powers Regulator Company, Chicago, Ill., a corporation of Illinois

Application September 4, 1936, Serial No. 64,717

Term of patent 14 years

To all whom it may concern:

Be it known that I, Morton O. Snediker, a citizen of the United States, residing at Chicago, in the county of Cook and State of Illinois, have invented a new, original, and ornamental Design for a Thermostat Mechanism, of which the following is a specification, reference being had to the accompanying drawing, forming part thereof.

Fig. 1 is a front elevation of a thermostat mechanism showing my new design, and
Fig. 2 is a side elevation thereof.

I claim:

The ornamental design for a thermostat mechanism, as shown.

MORTON O. SNEDIKER.
